UNITED STATES PATENT OFFICE.

ARCHIBALD SHARP, OF LONDON, COUNTY OF MIDDLESEX, ENGLAND.

VELOCIPED.

SPECIFICATION forming part of Letters Patent No. 415,740, dated November 26, 1889.

Application filed April 13, 1889. Serial No. 307,112. (No model.) Patented in England September 10, 1888, No. 13,043.

To all whom it may concern:

Be it known that I, ARCHIBALD SHARP, a subject of the Queen of Great Britain, residing at London, in the county of Middlesex, 5 England, have invented certain Improvements in Velocipedes, (for which I have obtained a patent in Great Britain, No. 13,043, bearing date September 10, 1888,) of which the following is a specification.

10 My invention relates to improvements in the frames of velocipedes; and the objects of my improvement are, first, to convert the frames of velocipedes into trusses, so that all the members of the said frames are either in 15 direct tension or compression; secondly, to thereby strengthen the said frames and at the same time reduce the weight thereof, and, thirdly, to generally increase the efficiency of these machines. I attain these objects by 20 constructing the frames of velocipedes as illustrated in the accompanying drawings, in which—

Figure 1, Sheet No. 1, is a side elevation, and Fig. 2, Sheet No. 1, a plan, of a front- 25 driving bicycle. Fig. 3, Sheet No. 1, is a side elevation of a rear-driving bicycle. Figs. 4 and 5, Sheet No. 1, are a side elevation and plan, respectively, of a single rear-driving tricycle. Figs. 6 and 7, Sheet No. 2, are side 30 elevation and plan, respectively, of a modification of a single rear-driving tricycle. Fig. 8, Sheet No. 2, is a view of a double-driving tricycle; and Figs. 9 and 10, Sheet No. 3, are views in elevation of tricycles for two riders. 35 All these machines are fitted with frames constructed according to my invention. Figs. 11, 11^a, and 12 are views in broken sectional elevation and plan, respectively, showing the construction of the steering hinge or joint. 40 Throughout these several views similar parts are marked with like letters of reference.

The frame consists, essentially, of two parts, hereinafter called "half-frames." Each half-frame in the case of a bicycle, as illustrated by Figs. 1 to 3, Sheet No. 1, of the accompanying drawings, supports one wheel, and in the case of a tricycle, as illustrated by Figs. 4 to 10, Sheets Nos. 1, 2, and 3, of the accompanying drawings, one half-frame supports one wheel and the other half-frame supports

an axle with a wheel at each end. This axle may carry the wheels and revolve in bearings carried by the half-frame; or the axle may be fixed to the half-frame and the wheels 55 revolve upon it. Each half-frame is made up of five members *a*, *b*, *b'*, *c*, and *c'*, which, together with the axle *x* of the wheel or wheels, are arranged similarly to the six edges of an irregular tetrahedron or triangular pyramid. 60 The member *a* is placed vertically or approximately vertically opposite and at right angles to the axle *x* of the wheel or wheels, and the members *b* *b'* and *c* *c'* run from the opposite ends of the member *a* to the ends of 65 the axle *x*, as illustrated, thus forming a double triangular fork. The members of the half-frame may be either tubes or bars. When the half-frame supports one wheel, the said wheel is mounted on the axle between the 70 members *b* *b'* and *c* *c'*; but when the half-frame supports two wheels the axle is prolonged and the wheels are placed outside the half-frame. The two half-frames are connected together by a hinge or joint. (Shown 75 on an enlarged scale by Figs. 11, 11^a, and 12, Sheet No. 4, of the accompanying drawings.)

In the ends of the tubular member *a* are placed cones *a'* *a'*², the latter being adapted to be adjusted with respect to the said tube. 80 These cones form centers for a spindle A, the ends of which are coned to adapt it to fit in the cones *a'* *a'*². At or near to each end of the other tubular member *a* are formed or fixed two arms A' A', adapted to support and carry 85 the coned spindle A, suitable slots *a*³ *a*³ being cut or formed in the tubular member *a*, carrying the coned centers, for the purpose of allowing the arms A' A' to pass therein and oscillate for the purpose of steering. 90

The pillar B for the saddle B' is mounted in the member *a* of one of the half-frames, and the pillar C for the handle-bar *c* is mounted in the member *a* of the other half-frame, the steering of the velocipede being 95 effected by the relative movement of the two half-frames. The crank-axle D, with its crank and chain-wheel, is mounted in bearings carried by the lower end of the member *a* of the half-frame carrying the driving 100 wheel or wheels.

By making the seat-pillar and handle-bar

of the velocipede of the same or approximately the same height the saddle and handle-bar may be made to interchange places, thus making the velocipede convertible from "rear driving" to "front driving," or vice versa. When the velocipede is used as a rear driver, a spring or springs may be introduced between the frames, if necessary, to assist in keeping the machine running in a straight line. In velocipedes having a pair of driving-wheels behind and a single steering-wheel in front, as shown by Figs. 8 to 10, Sheets Nos. 2 and 3, of the accompanying drawings, the upper ends of the members $b b'$ and $c c'$ are each united to form one member, as is illustrated, in order to give more room for the legs of the rider. In a velocipede made with a pair of driving-wheels, whether rear driving or front driving, in order that the bending movement on the wheel-axle x , due to the tension of the driving-chain, may be reduced to a minimum, I support the axle x by a third bearing near to the chain-wheel and carried by another member or tube c^2 , joining the members c and c' , where they converge to form one member, as illustrated by Fig. 8, Sheet No. 2, of the accompanying drawings. If the chain-wheel be placed exactly in the middle of the crank-axle—that is, between the axle-bearings—the member c^2 may be in duplicate. In velocipedes for two riders the half-frame carrying the driving-wheels is prolonged to get the necessary distance between the riders by using another vertical member a , braced to the other member a by longitudinal and diagonal members or bars $e e$, &c., as illustrated by Figs. 9 and 10, Sheet No. 3, of the accompanying drawings.

Those parts of the velocipede to which no special reference has been made, or which

are not fully illustrated in the drawings, present no novel features, and may be of the usual type or construction.

I am aware that prior to my invention the frames of velocipedes have been constructed in two parts hinged together at or about the center between the wheels for the purpose of steering such machines. I therefore do not claim such a combination, broadly; but

What I do claim as my invention, and desire to secure by Letters Patent, is—

1. In a velocipede the wheels of which are carried by two half-frames, each consisting of five members a , b , b' , c , and c' , forming an irregular tetrahedron, joining the said two frames together to form a steering-hinge by means of the vertical spindle A, carried by one of the members a , and the cones $a' a^2$, carried by the other member a , as set forth.

2. In a velocipede, the combination, with the two half-frames, each consisting of five members a , b , b' , c , and c' , of the seat-pillar B and the handle-bar pillar C, adapted to be interchanged, as and for the purpose set forth.

3. In a velocipede, the combination of the half-frames, each consisting of the members a , b , b' , c , and c' , the arms or brackets A' A' on the member a of the one half-frame and carrying the center spindle A, and the cones $a' a^2$, mounted in the member a of the other half-frame, substantially as set forth.

In witness whereof I have hereunto signed my name in the presence of two subscribing witnesses.

ARCHIBALD SHARP.
